UNITED STATES PATENT OFFICE.

THEODOR DANIELS, OF BROOKLYN, NEW YORK.

BOOKBINDER.

1,154,489.

Specification of Letters Patent. Patented Sept. 21, 1915.

Application filed November 27, 1914. Serial No. 874,332.

To all whom it may concern:

Be it known that I, THEODOR DANIELS, a citizen of the United States, residing at Brooklyn, in the county of Kings and State 5 of New York, have invented new and useful Improvements in Bookbinders, of which the following is a specification.

This invention relates to binders especially adapted to be used for holding books, 10 magazines, periodicals or the like and it consists in the novel features hereinafter described and claimed.

An object of the invention is to provide a binder of simple and durable structure 15 adapted to be easily and quickly manipulated for the purpose of securing the books or magazines therein and which may also be readily manipulated for the purpose of releasing the books or magazines.

With the above objects in view the binder 20 comprises a casing composed of two sections hingedly connected together and having at their ends transversely disposed plates which overlap each other. The said 25 sections are provided at their longitudinal edges with curls adapted to receive flexible strips of the covers of the binder the said curls also being adapted to receive rods whereby the strips are secured in the curls. 30 Toggle levers are pivotally connected with the sections at their outer ends and are pivotally connected at their inner ends with blocks which are screw threaded upon a shaft located between the sections. The 35 threads upon the shaft at the opposite ends thereof are disposed in opposite directions and consequently as the shaft is turned the blocks are moved either toward or away from each other simultaneously.

In the accompanying drawing, Figure 1 40 is a perspective view of the binder showing the manner in which a book or periodical is held in the same. Fig. 2 is a detailed plan view of the back portion of the binder in 45 open position. Fig. 3 is an end view of the same. Fig. 4 is a transverse sectional view of the same cut on the line 4-4 of Fig. 2. Fig. 5 is an enlarged detailed sectional view of the edge portion of one of the 50 sections of the binder. Fig. 6 is a detailed perspective view of parts of the binder the said parts being disconnected from each other.

The back of the binder comprises sections 55 1 which are hingedly connected together as at 2. The said sections are preferably formed from sheet metal. The sec-

tions 1 are provided at one end with transversely disposed plates 3 which overlap each other and at their opposite ends with transversely disposed plates 4 which also overlap each other. The plates 4 are provided at their inner portions with recesses 5 the object of which will be explained hereinafter.

The sections 1 are provided at their free 60 edges with longitudinally disposed inwardly directed curls 6. The edges of the said curls being spaced from the intermediate portions of the sections as best indicated in Fig. 4 of the drawing. A cover 7 is adapted to be applied to the back of the binder of which the sections 1 are components and the said cover is provided at its inner side with flexible strips 8 adapted to be inserted within the curls 6 of the sections 1 and when so 65 inserted rods 9 are inserted within the folds of the strips and within the curls whereby the strips are secured to the curls as best indicated in Fig. 3 of the drawing. It is apparent that by withdrawing the rods 9 70 75 80 85 90 95 100 105 110

the strips 8 are loosened or disconnected from the curls and the cover 7 may be detached from the back of the binder. The cover 7 may be rigid or flexible as desired. The sections 1 are provided at their inner 85 sides with inwardly disposed knuckles 10 arranged in pairs the pairs of knuckles being disposed in the vicinity of the ends of the sections 1. Eye-members 11 are positioned between the members of the pairs of 90 knuckles 10 and pivots 12 are passed through the knuckles and the eye members 11 and serve as means upon which the eye members 11 may swing with relation to the sections 1. As shown in Fig. 6 of the drawing the pivot 12 is in the form of a cotter pin although it is to be understood that any other suitable form of pivot may be employed. Toggle levers or links 13 are pivotally connected at their outer ends with the eye members 11 and the inner ends of the said levers are pivotally connected with blocks 21. A shaft 15 passes through the blocks 21 and is provided at its opposite end portions with threads 16 the threads at the opposite end portions of the said shaft being disposed in opposite directions as best indicated in Fig. 2 of the drawing. The shaft 15 is squared at one end as at 17 and the said squared portion is located opposite the recesses 5 in the plates 4. Consequently a key (not shown) may be inserted through the said recesses

and engaged with the squared portion 17 of the shaft 15 for the purpose of turning the said shaft. The levers 13 are provided with slots 18 which receive a pin 19 carried by a block 20, which is screw-serted on the shaft 15. The inner ends of the levers 13 are pivoted to a block 21 which is slidably mounted on the shaft 15. When the shaft 15 is turned the block 20 moves along the same and the pin 19 is carried along the slots 18, whereby the levers 13 are swung on the block 21 and thus the sections 1 are moved toward or away from each other.

From the above description taken in conjunction with the accompanying drawings it will be seen that when the shaft 15 is turned so that the blocks 14 are moved away from each other the toggle levers 13 are moved longitudinally and the free edge portions of the sections 1 are swung away from each other. When the free edge portions of the said sections have been sufficiently separated or spaced from each other the books or periodicals are inserted between the free edge portions of the sections and then by turning the shaft 15 to cause the blocks 14 to move toward each other the toggle levers 13 are moved longitudinally whereby the free edge portions of the sections 1 are

drawn toward each other and the books or periodicals are clamped between the free edge portions of the said sections. It is apparent that when it is desired to remove a book or periodical from the binder the operation just above described is reversed. Therefore it will be seen that a binder of simple and durable structure is provided and that the parts may be easily and quickly manipulated for the purpose of securing books or periodicals in the same or for removing the books and periodicals therefrom.

Having described the invention what is claimed is:—

A binder comprising sections, levers pivoted to the sections and having slots, a pin received in the slots, a block carrying the pin, a shaft upon which said block is screw-threaded, and another block slidably mounted on the shaft and to which the inner ends of the levers are pivoted.

In testimony whereof I affix my signature in presence of two witnesses.

THEODOR DANIELS.
